(57) **CLAIM**

The ornamental design for a caravan, as shown and described.

DESCRIPTION

The patent or application file contains at least one drawing executed in color. Copies of this patent or patent application publication with color drawing(s) will be provided by the Office upon request and payment of the necessary fee.

1. Caravan

1.1 is a front and left side perspective view of a caravan showing my new design;

1.2 is a left side elevation view thereof;

1.3 is a front elevation view thereof;

1.4 is a right side elevation view thereof; and

1.5 is a rear elevation view thereof.

1 Claim, 5 Drawing Sheets**(5 of 5 Drawing Sheet(s) Filed in Color)**(56)
